UNITED STATES PATENT OFFICE.

MIKE EMMER AND WILLIAM NATHANSON, OF CHICAGO, ILLINOIS.

RADIATOR CORE.

1,419,111.

Specification of Letters Patent. Patented June 6, 1922.

Application filed August 9, 1920. Serial No. 402,122.

To all whom it may concern:

Be it known that we, MIKE EMMER and WILLIAM NATHANSON, citizen of the United States, and residents of the city of Chicago, county of Cook, and State of Illinois, have invented certain new and useful Improvements in Radiator Cores, of which the following is a specification.

Our invention relates to improvements in radiator cores, and has for its object the provision of an improved construction of this character which is capable of being made of a minimum of material, strong and durable in construction and efficient in operation.

Other objects will appear hereinafter.

The invention consists in the combinations and arrangements of parts hereinafter described and claimed.

20 The invention will be best understood by reference to the accompanying drawings forming a part of this specification, and in which,

Fig. 1, is an end view of a portion of a radiator core embodying the invention,

Fig. 2, a side view of the same, with portions broken away to illustrate the interior arrangement,

Fig. 3, a transverse vertical section of the same,

Fig. 4, an enlarged perspective view, shown partially in section, of a portion of said core, and

Fig. 5, a horizontal section of the same.

35 The preferred form of construction, as illustrated in the drawings, comprises a plurality of parallel zig-zag water tubes, each of said tubes being made up of two adjacent zig-zag plates 5 and 6, the plate 6 having its edges inwardly offset at the points 7 and the plate 5 having its edges inwardly offset at the points 8 to bring the edges of said plates together but leave the usual water tube space 9 between them. These

40 water tubes are assembled in the core in the usual manner with zig-zag distancing plates 10 arranged between them and making flat contact alternately therewith as indicated. The plates 10 are provided with lateral vertical offsets 11 adjacent their edges, thus forming spaces which break the capillary attraction between the flat contacting areas of the plate 10 with the water tubes, so that when the edges of the core are dipped in 45 solder in the usual way the solder will only

be drawn upwardly between said edges by capillary attraction to the edges of the recesses 11, thus adequately securing the parts together but preventing waste of solder. These lateral offsets 11 also serve to stiffen 60 the construction of the core. The plates 5 and 6 are provided at their interior points of contact with the plates 10 with horizontal laterally extending ribs 12 consisting of smooth continuations to apexes of the adjoining inclined portions of said plates, thus materially facilitating the manufacture of said plates. Plates 10 are provided with correspondingly shaped grooves 13 to receive said ribs 12, such construction greatly facilitating proper assembling of the parts and stiffening the construction after assembly.

70 While we have illustrated and described the preferred form of construction for carrying our invention into effect, this is capable of variation and modification without departing from the spirit of the invention. We, therefore, do not wish to be limited to the precise details of construction set forth, but desire to avail ourselves of such modifications and variations as come within the scope of the appended claims.

Having described our invention, what we claim as new and desire to secure by Letters Patent is:—

85 1. A radiator core comprising water tubes spaced from each other; and a co-operating distancing plate between said tubes, there being a lateral offset adjacent the ends of said member to destroy the capillary attraction 90 between the contacting areas of said distancing plate and said tubes, substantially as described.

2. A radiator core comprising zig-zag water tubes spaced from each other; zig-zag co-operating members positioned between said tubes and alternately making flat contact therewith, there being lateral offsets in said co-operating members to destroy the capillary attraction between them, the edges 95 of said members being soldered together, substantially as described.

100 3. A radiator core comprising water tubes spaced from each other, each of said tubes comprising a zig-zag member and an adjacent corresponding zig-zag member soldered together adjacent the ends thereof, said members being inwardly offset to destroy the capillary attraction between them; and a distancing plate between said tubes having 110

an offset adjacent the ends thereof destroying the capillary attraction between the contacting areas, substantially as described.

4. A radiator core comprising parallel 5 zig-zag water tubes spaced from each other; zig-zag co-operating distancing plates positioned between said water tubes and contacting alternately therewith, there being lateral offsets in said distancing plates to destroy capillary attraction between them, the edges of said water tubes and said distancing plates being soldered together; laterally 10

projecting ribs at the contact points of said water tubes, there being corresponding grooves in said distancing plates to receive 15 said ribs substantially as described.

In testimony whereof we have signed our names to this specification in the presence of two subscribing witnesses.

MIKE EMMER.

WILLIAM NATHANSON.
